UNITED STATES PATENT OFFICE.

JOSEPH PEYSER, OF MOUNT VERNON, NEW YORK, ASSIGNOR, BY MESNE ASSIGNMENTS, TO ACKERMANN MANUFACTURING COMPANY, OF WHEELING, WEST VIRGINIA, A CORPORATION OF WEST VIRGINIA.

SEAMING MECHANISM.

1,408,713.

Specification of Letters Patent.

Patented Mar. 7, 1922.

Application filed March 30, 1918, Serial No. 225,701. Renewed August 8, 1921. Serial No. 490,731.

To all whom it may concern:

Be it known that I, JOSEPH PEYSER, a citizen of the United States, and a resident of Mount Vernon, county of Westchester, and 5 State of New York, have invented certain new and useful Improvements in Seaming Mechanism, of which the following is a specification.

The present invention relates generally 10 to can-seaming machines and has for its main object the automatic feeding and positioning of covers for application to cans that are placed manually upon the plunger or supporting means of an intermittently- 15 operated one-cycle machine.

Another object of the invention is to render the general design of the machine more compact so that all the operating parts may be enclosed or contained within a casing.

20 To this end, the invention consists in a machine of the character described having normally inactive actuating means for clamping and seaming which, when rendered active, operate for one cycle of the machine 25 and then stop, together with automatic means for positioning a cover, in line with a can on the supporting means, once during each cycle of operation of the actuating means.

30 Another feature of the invention resides in a general arrangement of the parts whereby the plunger-lifting cam is carried on a sleeve that revolves the seaming cam and thereby obviates the necessity of a counter 35 shaft and gearing for the same.

In the accompanying drawings there is shown a typical or illustrative embodiment of one concrete and preferred form of the invention, in which:

40 Figure 1 is a general side elevation, partly in section, with the upper casing broken away to expose the gearing of the machine.

Figure 2 is a front view of part of Fig. 1, looking in the direction of the arrow 2, also 45 with some of the parts in section.

Figure 3 is a horizontal sectional view on the line 3—3 of Fig. 2.

Figure 4 is a transverse sectional view on the line 4—4 of Fig. 3.

50 Figure 5 is a diagrammatic view showing the development of the plunger-lifting cam.

In the machine here chosen for illustration, suitable clamping means are employed that consist of a plunger 1 and a chuck 2.

The seaming means 3 may be of any desired 55 construction and is here represented as being of the same form as that shown in Fig. 3 of my application, Ser. No. 180,270, filed July 13, 1917, in which two seaming rollers, diametrically opposed to each other, are used 60 as the seaming tools, being mounted on a carrying member 4 that is pivotally supported and to which a swinging movement is imparted by means of rollers, such as 5, 65 engaging with a seaming cam 6. This seaming cam 6 is mounted on a cam sleeve 7 to which is imparted a single revolution during each cycle of operation of the machine while chuck 2 is given a continuous rotary motion at a relatively high speed in such manner 70 that, when plunger 1 is elevated to bring the can and cover into engagement with said chuck, said cam is rotated while the seaming tools are moved in and out in a manner understood by those skilled in the 75 art. A rotary motion is imparted to a shaft 8 that carries chuck 2 by means of bevel gears 9 and 10, the latter being mounted on a shaft 11 that receives its motion, by means of spur gears 12, from a power shaft 13. This 80 power shaft 13 is provided with a worm 14 meshing with a worm gear 15 having a hub 16 loosely mounted on shaft 8. Slidably mounted on cam sleeve 7, and rotatable in unison therewith, is a member 17 which is, 85 in effect, a clutch provided with teeth 18 that correspond to similar teeth on hub 16 so that, when sleeve 17 is moved into engagement with hub 16, the motion of shaft 13 is 90 imparted to cam sleeve 7. The controlling 90 means for effecting movement of sleeve 17 during one revolution, and for thereafter causing its rotation to cease may, of course, take many forms but, in the present instance, I mount a cam 19 fast on sleeve 7. 20 indicates a pivot on which is mounted an arm 21 having a roller 22 engaging with cam 19 and also having an extension 23 engaging in a groove 24 of the sliding member 17. The arm 21 is connected by means of link 100 25 to an upright rod 26 which, in turn, is suitably connected to a treadle 27 and from which extends also a connection 28 pivotally supported at 29 and engaging with one arm 30 the plunger 1. Upon depression of treadle 105 27, a can having previously been placed in position on said plunger, the upright rod 26 is depressed part way, thereby elevating

plunger 1 slightly and also lifting roller 22 out of the stop groove 31 of cam 19 and, at the same time, sliding sleeve 17 into clutch engagement with the worm wheel 15. This 5 transmits the motion from shaft 13 to cam sleeve 7 and causes one revolution of said sleeve. During the first part of said revolution, roller 22 travels over the surface 32 of cam 19 and then rises up the incline 33 10 to the high portion 34 of the cam. When this occurs, motion is transmitted back through lever 21, link 25, connecting rod 26, lever 28 and arm 30 to plunger 1 which is now raised all the way up thereby clamping 15 the can and cover securely between said plunger and chuck. The timing of the seaming cam is of such character that the seaming tools now move in, one at a time, toward the can and cover and perform the seaming 20 operation in a well understood manner. Continued rotation of sleeve 7 eventually brings roller 22 from the high point 34 of cam 19 to the notch or depression 31, thereby moving the sliding member 17 out of clutching 25 engagement with worm wheel 15 and arresting rotation of cam sleeve 7, said roller 22 and said depression 31 forming a positive stop.

In machines of this character heretofore 30 it has generally been customary for the operator to place both the can and cover in position on the plunger after which the seaming operation was effected. The contents of the can being very hot necessitates 35 the use of thick and cumbersome gloves on the hands of the operator. These unwieldy gloves make it particularly difficult for the operator to handle a light and small cover and to place it accurately on the can, as 40 will readily be understood. Therefore, I have provided means by which it is only necessary for the operator to place a can upon the plunger and start the machine in operation, automatic means being provided 45 for feeding a cover from a magazine into position on the can that has been placed on the plunger. In the present instance, these means take the following form. 35 indicates a bracket carried by the machine and 50 provided with a groove or dove-tail portion 36, as shown, in which reciprocates a slide 37 having a knife 38. Suitable means are provided for effecting a to-and-fro movement of this slide, in the present instance 55 taking the form of an eccentric 39 that may be conveniently carried by cam sleeve 7. In Fig. 3, this eccentric is shown in lines of dots and dashes since the section is taken on the line 3—3 indicated in Fig. 2; and 60 the eccentric is in a plane above the point where the section is taken, as will be seen in Fig. 1. Connected to this eccentric 39 is an arm 40 secured to a bell crank 41 pivotally supported at 42 and connected by 65 means of a link 43 to an oscillating lever

44 pivotally supported at 45. At its outer free end, lever 44 carries a pin 46 extending up through a slot 47 in bracket 35 and connected to slider 37. Carried by bracket 35 and located adjacent to chuck 2 is a cover 70 magazine 48 in which a plurality of covers 49 are superposed on each other. When the parts are in the position shown in Figs. 2 and 3, the lowermost cover 49 will have dropped down on the surface 50 of 75 bracket 35 and will be below the hopper proper with the knife 38 behind it, the upper surface of said knife being in line with the lower part of the hopper and acting, during what may be called the forward reciprocation, to cut off the next superimposed cover. During such forward movement of slider 37, the surface 51 of said slider will hold the next cover in position and keep it from falling down. As the 80 cover advances toward the can on plunger 1, it will be carried by slider 37 and edge-wise displacement of the cover will be prevented by reason of flanges 52 until it is brought into position in line with head 53 90 directly on the can on plunger 1 and in line with chuck 2. The can now being elevated, the cover will be pressed into proper relation with the can and the seaming operation may take place. The eccentric 39 and 95 the parts connected with it are so timed and so related that, at the beginning of a cycle of the machine and while the roller 22 is traveling on the surface 32 of cam 19, a cover is moved from an intermediate position, indicated in dotted line 54, directly into line with the can on plunger 1, the arm 44 occupying, at the beginning of the cycle, substantially the position indicated in dotted lines at 55 and then initially moving to the 100 right in Fig. 3. The arm 44 then returns until the knife 38 occupies approximately the position shown in Fig. 2 after which the arm moves forward again to bring a cover from the magazine into intermediate position and, when it reaches that position, one 105 cycle of operation has been completed and operation of the machine ceases until it is again actuated by depression of treadle 110 27 by the operator. 115

I claim:

1. An intermittently-operating one-cycle seaming machine comprising: a chuck, a plunger in line with the chuck, a seaming member, a shaft carrying the chuck and making a plurality of revolutions during each cycle of operation of the machine, means for rotating the shaft continuously, a rotatable sleeve surrounding the shaft and making one revolution during each cycle of operation of the machine, a plunger-lifting cam and a seaming cam both mounted on the rotatable sleeve, means for actuating the sleeve, connections from the plunger-lifting cam to the plunger including a clutch ele- 125 130

- ment for connecting and disconnecting the sleeve from its actuating means, means for positioning a cover in line with the can on the plunger, an actuating member for said 5 positioning means carried by the sleeve, and connections from said actuating member to said positioning means.
2. An intermittently-operating one-cycle seaming machine comprising: a chuck, a 10 plunger in line with the chuck, a seaming member, a shaft carrying the chuck and making a plurality of revolutions during each cycle of operation of the machine, means for rotating the shaft continuously, 15 a rotatable sleeve surrounding the shaft and making one revolution during each cycle of operation of the machine, a plunger-lifting cam and a seaming cam both mounted on the rotatable sleeve, means for actuating the 20 sleeve, connections from the plunger-lifting cam to the plunger including a clutch element for connecting and disconnecting the sleeve from its actuating means, means for positioning a cover in line with the can on
- the plunger, an eccentric for said positioning means carried by the sleeve, and connections from said eccentric to said positioning means. 25
3. An intermittently-operating one-cycle seaming machine comprising: can supporting and clamping means, seaming means, normally inactive actuating means for said two means, which, when rendered active, operate for one cycle of the machine and then stop, a cover magazine adjacent the supporting and clamping means, and automatic means having a to-and-fro movement for transferring during each cycle of the machine one cover from a position intermediate the magazine and supporting means to a 30 position in line with a can on the supporting means and for transferring another cover from the magazine to the intermediate position. 35

Signed at Mount Vernon, in the county 45
of Westchester, and State of New York,
this 25th day of March 1918.

JOSEPH PEYSER.
